UNITED STATES PATENT OFFICE.

ERNEST W. PADEFORD, OF ATTLEBORO, MASSACHUSETTS, ASSIGNOR TO DAVID A. HART AND DEXTER E. PARTELOW, A FIRM DOING BUSINESS AS RELIANCE MANUFACTURING COMPANY, OF PROVIDENCE, RHODE ISLAND.

BUCKLE.

1,159,328.

Specification of Letters Patent.

Patented Nov. 2, 1915.

Application filed May 6, 1915. Serial No. 26,290.

To all whom it may concern:

Be it known that I, ERNEST W. PADEFORD, a citizen of the United States, residing at Attleboro, in the county of Bristol and State of Massachusetts, have invented certain new and useful Improvements in Buckles, of which the following is a specification.

My invention relates to buckles or clasps for belts and similar articles.

The essential objects of my invention are to enable the belt to be readily adjusted by merely sliding one member relatively to the other; to insure a continuous and positive clamping action of the buckle upon the belt; to avoid the use of solder; and to attain the desired ends in a simple and inexpensive structure.

To the above ends essentially my invention consists in such parts and combinations of parts as fall within the scope of the appended claims.

In the accompanying drawings which form a part of this specification, Figure 1 is a front elevation of a buckle embodying my invention, Figs. 2 and 3, top and bottom elevations of the same, Fig. 4, a rear elevation, Figs. 5 and 6, sections of the same on line α α of Fig. 4, showing the parts in open and clamped positions respectively, and Fig. 7 a detail view of the clamping member.

Like reference characters indicate like parts throughout the views.

My device comprises a curved face plate A having rearwardly directed top and bottom flanges B, provided with spaced longitudinally disposed slots b near their rear margin, together with oppositely disposed perforations b' intermediate the slots, and somewhat nearer the face plate than the slots. A slideable back plate C has lateral lugs or projections c registering in the slots, and slideable therein. Upon the end of the back plate is a loop D adapted to receive one end e of a belt E. The opposite end of the belt is represented by the reference character e' . Centrally located in the plate C

is a transverse slot f . A bar G has rounded end portions or trunnions g mounted in the perforations b' of the side plates. The bar G is substantially flat, as at g' , and has extending therefrom at an angle thereto a flange g^2 . A lug h on the plate g extends therefrom at an angle thereto, and at an angle to the flange or portion g^2 . The member h loosely registers in the slot f , so that when the plate C is reciprocated in one direction the clamping flange g^2 tightly engages the end e of the belt against the rear surface of the face plate as shown in Fig. 6, and when the plate is reciprocated in the opposite direction the member g^2 is elevated adjacent to or into contact with the inner face of the plate C thereby allowing the belt end e' free passage through the buckle as shown in Fig. 5.

Under normal conditions of wear the tension of the belt end engaging the loop D causes the flange g^2 to grip the opposite end of the belt. The greater the tension, the greater the grip. It will be observed that the entire structure comprises merely thin metal parts capable of being bent up and pierced with little or no expense or labor. 75

What I claim is:—

1. In a buckle or clasp, the combination of a face plate, flanges on the plate, a clamping member rotatably mounted in the flanges, and a reciprocating member slidably mounted in the flanges for rotating the clamping member.

2. In a buckle or clasp, the combination of a face plate, flanges on the plate provided with longitudinal slots, a back plate, lateral projections on the back plate loose in said slots, a bar rotatably mounted in the flanges, a flange upon the bar extending toward the face plate, and a lug on the bar engaging the back plate.

3. In a buckle or clasp, the combination of a curved face plate, flanges on the plate provided with longitudinal slots, a curved back plate provided with a central transverse slot, lateral projections on the back plate slideable in the first slots, a bar pivot-

ally mounted in the flanges intermediate the slots, an inclined flange on the bar directed toward the face plate, a lug on the bar inclined in a direction opposite to the inclination of the flange and loosely registering in the slot in the back plate, and a loop on the back plate.

In testimony whereof I have affixed my signature in presence of two witnesses.

ERNEST W. PADELFORD.

Witnesses:

HORATIO E. BELLOW,
CHARLES S. JENCKES.
